UNITED STATES PATENT OFFICE.

ERNEST P. PIERCE, OF LORAIN, OHIO.

PLUG FOR OIL-HOLES.

1,169,189.

Specification of Letters Patent. Patented Jan. 25, 1916.

Application filed October 18, 1915. Serial No. 56,514.

To all whom it may concern:

Be it known that ERNEST P. PIERCE, a citizen of the United States, residing at Lorain, in the county of Lorain and State 5 of Ohio, have invented certain new and useful Improvements in Plugs for Oil-Holes, of which the following is a specification.

My invention pertains to plugs for the oil holes in machinery of different kinds, all 10 substantially as shown and described.

In the accompanying drawings I show several forms or styles of plugs which embody my invention, one form of which is shown in Figures 1, 2 and 3. In this form 15 the plug has a head with substantially semi-spherical sides and a section thereof is shown in Fig. 1 in an oil hole and a section of a shaft therewith, and Fig. 2 is a side elevation of the plug in Fig. 1. Fig. 3 is a 20 cross section on line 3—3, Fig. 2. Fig. 4 shows a modification of the plug in that it has a flat sided head, and Fig. 5 is a side elevation of Fig. 4 showing the said side milled to facilitate gripping. Fig. 6 shows 25 a plug with flaring top sides and Fig. 7 is a cross section on line 7—7, Fig. 6.

The article as thus shown in the several forms or shapes is designed for use in oil holes to protect the holes and the oil from 30 foul accumulations, such as dust and dirt, and in all the forms shown, the article is represented as fashioned from a single piece of spring metal in suitable dies according to the shape desired, and then bent and 35 drawn as will presently appear. Thus, in Figs. 1 and 2 a style of plug is shown which has a split or divided body 2, with approxi-

40 mately semi-circular or concave-convex head portions 3 and a drawn integral point 4. Having struck up the blank to form this plug the blank is pressed to the shape shown in the respective sides thereof and then bent back upon itself at the middle, and the point or extremity is drawn to shape. This drawing is necessary because thereby the sides 45 of the plug become set and fixed in close or nearly closed relations, leaving only what may be termed a slit between them and which provides for a slight compression of 50 the sides when the plug is pressed into the hole to get a close fit. The head affords a grip for the hand and limits the entrance of the plug in the hole, and the split at the

center enables a tool to be inserted to draw the plug out of a hole. By making the plug 55 slightly tapered it can be driven in so tightly that it will not work or lose out and it is then especially that the entrance of a tool in the head facilitates removal.

In Figs. 4 and 5 the same construction is 60 shown as in Figs. 1 and 2 except that the head portions have flattened and milled surfaces 6 to make an effective hand grip.

In Fig. 6 the head of the plug is shown as flaring as indicated by 7, and in this respect the plug is substantially the opposite 65 of Figs. 1 and 4. Otherwise this plug is the same as Figs. 1 and 4.

The one essential feature common to all the plugs shown herein and others that 70 might be suggested, is the drawn end of the plug, and which is the finishing act in its manufacture. This also is most important because thereby the plug is caused to retain and hold its shape rather than spring open 75 as it would if drawing did not occur. The split formation is important also as it affords vent for the oil and admits air enough to insure free lubrication while it excludes the dirt. Heretofore, it has been largely the 80 practice to use screw threaded plugs for this purpose, but besides the time consumed in their use they tend to close the oil hole so perfectly that the plug holds back the oil from feeding. I purposely provide for such 85 feed by slightly enlarging the slit at the bottom thereof as shown at 10. My plug can be instantly inserted and driven in when necessary and can be as quickly and easily removed.

It will be seen that the plug is tubular, with a hollow body, open at one end and closed at the other by the integral portion 4 and that the said end is rounded and pointed and with the opening 10 exposed at the 90 bottom to admit air to the oil. The cross section of the body in Figs. 3 and 7 show the tubular or cylindrical effect, and the spring of the sides of the body is such that the said sides can be pinched together on the split or slit between them when the plug is inserted in a hole. Hence practically no time at all is required to apply a plug after 95 oiling and it is also as quickly removed. Obviously also, since the plug is machine 100 made out of comparatively light metal it is

an inexpensive plug to manufacture and to the trade. In Fig. 1 B represents a shaft bearing and S a shaft therein.

What I claim is:

- 5 1. A plug for oil holes consisting of sheet metal and having a hollow tapered body and a round head in one piece.
2. A plug for oil holes as described consisting of sheet metal and having opposite 10 sides and a divided head and said sides and head spaced at their edges.
3. A plug for oil holes as described formed in a single piece of metal and having two 15 sides with body and head portions circular in cross section and said sides integral at their lower ends.
4. A plug for oil holes as described having a tubular body divided lengthwise at its middle and having a rounded portion 20 at one end uniting said sides and a head portion on each side.
5. A plug for oil holes having a tubular

body split lengthwise and an integral portion at the bottom of said split drawn to a rounded shape and provided with a head 25 portion on each side of said split.

6. A plug for oil holes as described having an integral end and a tubular body split lengthwise above said end and constructed to vent the plug, the said body being open 30 at its top and provided with half of a head at each side.

7. A plug for oil holes as described having a split-tubular body open at its top and connected at its bottom and provided with 35 a head having opposite sides of substantially semi-spherical shape.

In testimony whereof I affix my signature in presence of two witnesses.

ERNEST P. PIERCE.
